CLAIM

The ornamental design for a water bottle as shown and described.

DESCRIPTION

FIG. 1 is a perspective view of a water bottle showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view thereof along line 8-8 in FIG. 2.

The broken lines shown in the figures are for the purpose of illustrating portions of the water bottle and form no part of the claimed design. The oblique line shading in the Figures shows a transparent surface and not surface ornamentation. The dot-dot-dash broken line arrows in the FIG. 2 is used to identify the cross-section view, is for reference purposes only, and forms no part of the claimed design. The broken lines and solid lines parallel staggered shown in FIG. 8 indicate the transparent cross-section of the claimed design and form no part thereof.
